ELECTRIC MAT SWITCH

Chamberlain Ferry, Kensington, and Sheldon S. Roby, Meriden, Conn., assignors to The Stanley Works, New Britain, Conn., a corporation of Connecticut

Application October 2, 1958, Serial No. 764,792

12 Claims. (Cl. 200—86)

This invention relates to mat switches for controlling the operation of electrically actuated doors or the like in response to pressures such as those applied to the mat by persons stepping thereon.

A major object of the present invention is to provide an improved electric mat switch having a uniform sensitivity to pressures applied to any point within an area comprising a major portion of its surface.

Another object is to provide an improved electric mat switch which is economical to construct and assemble and which lends itself to mass production techniques.

Another object is to provide a mat switch of the multiple plate type so constructed and arranged that the contact-making pressure is applied to a plate which is substantially nonflexible as to localized areas but which is mounted to transfer downward forces to a flexible plate in a manner to insure positive circuit-making contact between nonflexible and flexible plates.

Another object is to improve and simplify the spacing elements employed between the contact-making plates of switches of the character described which may be fabricated at a low cost.

Other objects will be in part obvious and in part pointed out more in detail hereinafter.

The invention accordingly consists in the features of construction, combination of elements and arrangement of parts which will be exemplified in the construction hereafter set forth and the scope of the application of which will be indicated in the appended claims.

In the drawings:

Fig. 1 is a fragmentary view in vertical section showing a carpet contact switch assembly incorporating the present invention with no pressure applied thereto and the contacts in open position.

Fig. 2 is a view showing the device of Fig. 1 under pressure such as is applied by a person walking thereon, with the contacts in closed position.

Fig. 3 is a similar view of a carpet contact switch assembly showing an alternate embodiment of the invention.

Fig. 4 is a view showing the device of Fig. 3 under pressure such as is applied by a person walking thereon, with the contacts in closed position.

Fig. 5 is a top plan view of a carpet contact switch assembly with portions broken away to disclose the assembly of plates and spacers.

Fig. 6 is a fragmentary perspective view exploded to illustrate the spacer and plate assembly of the device of Fig. 5.

Fig. 7 is a top plan view of the carpet switch assembly of Fig. 3 with portions broken away to disclose the assembly of plates and spacers.

Fig. 8 is a fragmentary perspective view exploded to illustrate the spacer and plate assembly of the device of Fig. 7.

Referring to Fig. 1, a mat switch constructed in accordance with the present invention includes a pair of metal plates 12 and 14 normally maintained in parallel

2

spaced-apart relation by spacers or stencils 16, with the plate assembly enveloped in a resilient housing-like mat 18 internally chambered throughout a major portion thereof to receive the paired plates between a top wall portion 20 and a bottom wall portion 22, mat 18 being constructed in a manner that the top and bottom walls are normally in spaced parallel relation as shown in Fig. 1. The bottom wall 22 of mat 18 is provided with integral supporting ribs 24 to maintain a major portion of that wall spaced above a supporting surface such as a floor 26, illustrated dotted, when the switch is not under pressure. The ribs 24 are disposed in staggered relationship with respect to the spacers 16 and form supports for sheet 14 which are offset relative to the spacers 16.

As shown in Figs. 1 and 2, the upper contact plate 12 is of heavy metal sheet stock which resists flexing under the weight of a person stepping onto upper wall 20, while lower contact plate 14 is of relatively light metallic sheet stock which readily flexes under that weight. While there may be slight over-all flexing of plate 12, such flexing as may occur is not of a localized nature, nor does it materially contribute to the operation of the switch. Plate 12 does however move downwardly as a unit under the weight of a person stepping on resilient mat 18, but such downward movement is due to compression of the mat, mat 18 being of a deformable electrically insulating material such as plastic or rubber material or the like.

Operation of the switch shown in Figs. 1 and 2 is as follows: Pressure applied to top wall 20 is transferred to top plate 12 which rests on spacers 16 which are in turn supported on the relatively flexible plate 14 which, in turn, is supported on the upper surface of the lower wall 22. Spacers 16 are of an electrical insulating material which does not compress appreciably under the weights involved, hence, due to the rigidity of upper plate 12 which prohibits any appreciable flexing between the spacers, the downward forces are transferred to lower plate 14 solely through spacers 16. It will be seen that the spacers 16 are laterally offset from the supporting ribs 24 of the lower mat wall 22. Preferably, all but those spacers closest the margins of the mat are positioned midway between the ribs 24. The marginal spacers are at positions inwardly of the supporting ribs at the mat margin and above a portion of lower wall 22 which is normally spaced above supporting surface 26. Electrical terminals 25, 27 which are connected to the plates 12 and 14, respectively, lead to the edge of the mat for connection to an electrical door operator circuit.

The weight of a person stepping on any portion of the upper mat surface inwardly of marginally reduced portions 28 results in downward forces applied to at least one, and in most instances to two or more of the spacers 16 to flex downwardly one or more of the local areas of lower plate 14 on which the spacers rest. Since localized areas of plate 14 so flexed are in turn supported on corresponding areas of the flexible lower mat wall 22, which is spaced by ribs 24 above the floor, those areas of the lower plate are thus resiliently mounted, hence they readily flex downwardly under such applied forces, as shown in Fig. 2. However, since the areas of lower plate 14 directly above the supporting ribs 24 are not free to flex in the above manner, corresponding areas of upper plate 12 are moved into firm circuit closing engagement therewith as the mat is compressed under a weight above a predetermined minimum. The switch is designed to operate under a predetermined weight selected in view of its intended use. Spacers 16 are separated at distances which insure positive contact, hence a good electrical connection, between the upper and lower metallic

plates, in response to applied pressures at any position throughout the mat surface inwardly of the relatively narrow marginal portion 28.

A stencil or spacer construction particularly useful in this invention is illustrated in Figs. 4 and 5. Fabrication costs are reduced by employing a single stencil 30 formed of a sheet of good electrical insulating material such as cardboard, plastic, or the like, with rectangular or other shaped portions cut therefrom to define, for example, a plurality of transverse spacers 32 which correspond to spacers 16 above described in respect to the structure of Figs. 1 and 2. The resulting mat switch, as shown in Fig. 4, closely resembles the construction illustrated in Figs. 1 and 2, a resilient mat 34 being broken away to show a heavy upper plate 36, spacer element 30, a lower flexible plate 38 viewable through the apertures of element 30, and a plurality of supporting ribs 40, shown dotted, and preferably provided in the manner above described as integral extensions of the lower mat wall, not shown. Marginal strips 42, on each side of spacer element 30, are positioned in abutment with integral marginal ribs 44 of mat 34 which correspond to the marginally reduced areas 28 of the structure of Figs. 1 and 2. Mat 34 is preferably constructed of a plastic material.

The stencil and support structure for the lower flexible plate can, of course, take other form. For example, as seen in Figs. 3, 4, 7, and 8, stencil 50 is provided with a plurality of closely spaced relatively large circular apertures 51 and is positioned between substantially rigid upper plate 52 and flexible lower plate 53. A resilient upper mat 54 and a resilient bottom wall 55 are provided in a similar manner as with the embodiment described in Figs. 1 and 2. Bottom wall 55 supports flexible plate 53 and is provided with a plurality of spaced raised portions or button-like projections 56 which engage the supporting floor surface, thereby to support the mat switch. As most clearly seen in Fig. 7, wherein portions of top plate 52 and upper carpet surface 54 have been broken away, raised portions 56 are generally circular in lateral cross-section and extend from a portion of maximum height or vertical cross-section 56a (shown dotted) to a portion of minimum height or vertical cross-section 56b (shown dotted) and are arranged so that the point 56a of maximum height is vertically aligned and substantially concentric with apertures 51 in spacer 50.

Thus, as a downward force is exerted on substantially rigid top plate 52 by a person walking on upper carpet surface 54, spacer 50 moves downwardly with plate 52 to deform lower support 55 so as to bring lower support portion 56b into contact with the supporting surface and thereby deform flexible lower plate 53 into engagement with upper plate 52 in the region of maximum cross-section 56a of buttons 56. This engagement establishes electrical contact between plates 52 and 53 to close an external electrical circuit between the terminals 60 and 61 which are electrically connected to lower plate 53 and upper plate 52 respectively.

It is thus seen that by employing one or more rigid contact plates which resist flexing, in combination with a contact plate which readily flexes, a simplified switch of unusual ruggedness and dependability of operation results. One of the basic requirements of such a switch is that at least some of the contacts remain closed as a person walks over the mat. Tests indicate that mat switches incorporating the above concepts remain closed as long as any portion thereof, except of course the extreme margins, is subject to the minimum predetermined actuating pressure.

As will be apparent to persons skilled in the art, various modifications and adaptations of the structure above described will become readily apparent without departure from the spirit and scope of the invention, the scope of which is defined in the appended claims.

We claim:

1. In an electric mat switch, the combination com-

prising a rigid top plate, means supporting said top plate for downward movement as a unit, a flexible second plate, spacing means interposed between said top plate and said second plate, said spacing means defining a plurality of open areas where said flexible second plate can be deformed into contact with said rigid top plate, and support means for said second plate, said support means having a varying cross-section with a plurality of raised portions positioned in vertical alignment with said open areas whereby depression of said top plate causes deformation of said second flexible plate in the region of the raised portions of said support means and into engagement with said top plate.

2. In an electric mat switch, the combination comprising a rigid top plate, means supporting said top plate for downward movement as a unit, a flexible second plate, spacing means disposed between said top plate and said second plate and engageable with said top plate and said second plate at spaced intervals, and means supporting said flexible second plate at spaced intervals, the points at which said last named means support said flexible second plate occurring intermediate the points at which said spacing means is engageable with said top plate and said flexible second plate.

3. In an electric mat switch, the combination comprising a rigid top plate, means supporting said top plate for downward movement as a unit, a flexible second plate, a spacer between said top plate and said second plate, said spacer having a plurality of apertures formed therein, and a support for said second plate, said support having a plurality of raised buttons thereon, said buttons being vertically aligned with the apertures in said spacer.

4. In an electric mat switch, the combination comprising a rigid top plate, means supporting said top plate for downward movement as a unit, a flexible second plate, a spacer interposed between and engaging said top plate and said second plate, said spacer having a plurality of apertures formed therein, and a flexible support for said flexible second plate, said flexible support engaging said flexible second plate throughout one surface thereof and having a plurality of depending buttons formed thereon, said buttons being in vertical alignment with the apertures in said spacer.

5. In an electric mat switch, a rigid top plate movable downwardly as a unit, a flexible second plate parallel to the rigid top plate, a plurality of separated non-compressible spacers between the rigid top plate and the flexible second plate, and a plurality of spaced supports for the flexible plate disposed in staggered relationship with respect to said spacers.

6. In a device of the character described, a resilient mat having embedded therein parallel to the major plane thereof a rigid metal plate, a flexible metal plate, a plurality of electrically insulating relatively non-compressible spacer elements positioned at intervals between said plates to maintain them in parallel spaced relation, and supporting means for said flexible plate disposed on opposite sides of the spacer elements to permit deformation of the flexible plate by forces acting through said spacers when pressure is applied to said rigid plate.

7. In an electric mat switch, a rigid metal plate, a flexible metal plate, electrically insulating spacers disposed at intervals between said plates to maintain them in substantially parallel spaced relation, and a resilient electrically insulating mat enclosing said plates and maintaining them engaged with said spacers, said mat having a contoured lower wall of varying cross section supporting said flexible metal plate and permitting deformation of said flexible metal plate in the regions between said spacers by forces acting through said rigid plate and said spacers.

8. In a device of the character described, a mat of resilient material provided with an internal chamber having upper and lower walls, said mat having a lower wall provided with spaced depending portions engageable with

a supporting surface, a flexible metallic plate on the lower wall of said chamber, electrically insulating spacers disposed at intervals on said flexible plate in staggered relationship to said depending portions, and a relatively non-flexible metallic plate supported on said spacers in spaced relation above said flexible plate.

9. In a switch of the floor mat type, an upper relatively heavy metal plate which resists flexing under switch actuating pressures and a lower relatively light plate which flexes under said pressures, spaced apart separators of non-conducting material intermediate said plates to normally maintain the plates in parallel spaced relation, and spaced apart supporting means intermediate said spacers and below said lower plate for contact with a supporting surface, whereby switch actuating pressures applied to said upper plate are transmitted through said separators to non-supported areas of said lower plate to cause flexure thereof and circuit closing contact between said plates in portions intermediate said separators.

10. In a switch of the floor mat type including relatively heavy upper and lower spaced metal plates which resist flexing under switch closing pressures and a relatively thin metal plate which flexes under such pressures positioned in parallel spaced relation therebetween, spaced apart upper separators of non-conducting material between said upper and intermediate plates, and spaced apart lower separators between said lower and intermediate plates, said lower separators being positioned substantially midway between said upper separators, whereby application of pressure to said upper plate causes said upper separators to flex said light plate to effect switch closing contact between the portions of said heavy upper plate and said thin metal plate disposed above the lower separators.

11. A switch of the floor mat type for controlling door actuating mechanisms and the like comprising two super-

posed generally parallel imperforate sheet metal plates, the upper plate being sufficiently rigid to resist flexing responsive to predetermined operating pressures and the lower plate being sufficiently flexible to be deformed under those pressures, means normally separating the plates in said parallel relation comprising a plurality of spaced-apart non-conducting and substantially non-compressible elements disposed intermediate the plates, and means resiliently mounting said lower plate in the area of said spacers to permit operating pressures applied to said upper plate to move said upper plate as a unit toward said lower plate and cause said spacers to deform portions of said lower plate and permit switch closing contact between the upper and lower plates in areas of said lower plates not deformed by said spacers.

12. In a device of the character described, a mat of resilient electrically insulating material provided with an internal chamber extending parallel to the major plane of the mat, a rigid metal plate, a flexible metal plate, said plates being disposed in said chamber, a plurality of electrically insulating and relatively non-compressible elements positioned at intervals intermediate said plates to normally maintain the plates in substantially parallel spaced relation with the rigid plate adjacent the upper wall 20 of the chamber and the flexible plate adjacent the lower chamber wall, the bottom of said mat being contoured to support portions thereof in the area of said insulating elements above a supporting surface to permit flexing of corresponding areas of said flexible plate by pressure 25 applied to said rigid plate and transmitted to said flexible plate through said insulating elements.
